UNITED STATES PATENT OFFICE.

RASMUS P. CHRISTENSEN, OF BUFFALO, NEW YORK.

ROTARY PUMP.

No. 852,137

Specification of Letters Patent.

Patented April 30, 1907.

Application filed June 19, 1906. Serial No. 322,433.

To whom it may concern:

Be it known that I, RASMUS P. CHRISTENSEN, a citizen of the United States, residing at Buffalo, in the county of Erie and State of New York, have invented certain new and useful Improvements in Rotary Pumps, of which the following is a specification.

This invention relates to rotary-pumps, and its object is the production of a simple, inexpensive, and effective pump having few parts which can be easily assembled and disassembled.

The invention consists in the construction, arrangement, and combination of parts to be hereinafter described and particularly pointed out in the appended claims.

In the drawings,—Figure 1 is a central vertical section of a pump embodying my invention. Fig. 2 is a horizontal section taken on line 2—2, Fig. 1, the piston being shown in elevation. Fig. 3 is a horizontal section taken on line 3—3, Fig. 1, the piston being in its central forward position. Fig. 4 is a section taken on line 4—4, Fig. 2. Fig. 5 is a section taken on line 5—5, Fig. 2. Fig. 6 is a detached perspective view of the valve or abutment.

Referring to the drawings in detail, like letters of reference refer to like parts in the several figures.

The reference letter A designates the casing of the pump provided with a piston-cylinder B, a valve or abutment-chamber C opening into the piston-cylinder, an inlet-passage D beneath the valve or abutment-chamber opening into the piston-cylinder adjacent the inner end of said chamber, and an outlet-passage E adjacent said chamber.

To render the interior of the piston-cylinder and the abutment-chamber easily accessible, they are closed at each end by a removable head F; both heads being secured to the flanges δ of the casing by suitable bolts f .

An inlet-pipe d is bolted to the outer end of inlet-passage D, and an outlet pipe e is bolted to the outer end of outlet-passage E.

Extending centrally through cylinder B is a crank-shaft G having cast thereon two piston-members g . Said crank-shaft has its central crank or offset portion g' located between adjacent ends of said piston-members.

An abutment or valve H is secured to the crank-shaft between the piston-members; it having a flat portion h reciprocal in the abutment-chamber and a cylindrical portion h' secured to the crank-shaft between the pis-

ton-members. Said cylindrical portion is loosely attached to the shaft so that the latter may rotate therein while carrying the piston through a circular course within the cylinder.

One-half of the cylindrical portion of the abutment is cast integrally with the flat portion thereof and may for convenience be termed the integral half, and the other or removable half is in the form of a semi-cylindrical cap I secured to the integral half by screws i and having a smaller radius than said integral half. The integral half of the cylindrical portion of the abutment has its peripheral face cut-away, as at J, on a radius coincident with that of the cap portion thereof, and enclosing said cap-portion with the ends fitting into said cut-away portions is a curved face-plate K secured by screws j entering the integral half of said cylindrical portion.

The cylindrical portion of the abutment, considered as a whole, is of the same diameter as the piston-members, and by reason of its occupying the space between said members, serves as a part of the piston. The flat portion of the abutment extends from head to head of the casing, and at its inner end is provided with a double beveled-edge, which bears against the piston-members. The free or outer end of the abutment bears constantly against the bottom of the abutment-chamber and is moved back and forth therein, while the connected end travels through a circular path.

The crank-shaft passes through suitable stuffing-boxes in the heads of the casing, and at one end of said shaft is a pulley by means of which the piston is revolved.

When the piston travels forward and upward in the direction indicated by the arrow in Fig. 1, the liquid or other matter being pumped is drawn into the cylinder by the suction created, the liquid or matter in the space above the piston or between the same and the casing is expelled through the outlet. The suction on the under side and the pressure on the upper side of the abutment acts to hold the free end of the abutment firmly against the bottom of the abutment-chamber, thereby positively preventing leakage through the abutment-chamber.

Having thus described my invention what I claim is,

1. In a rotary-pump, a casing comprising a cylindrical portion having an inlet and an

outlet, and an abutment-chamber between the said inlet and outlet, a crank-shaft passing through said cylindrical-portion, a piston comprising two members secured to said shaft on opposite sides of the crank thereof, and an abutment movable in said abutment-chamber and secured to said crank.

2. In a rotary-pump, a casing comprising a cylindrical portion having an inlet and an outlet, and an abutment-chamber between the said inlet and outlet, a crank-shaft passing through said cylindrical-portion, a piston comprising two members secured to said shaft on opposite sides of the crank thereof, and an abutment movable in said abutment-chamber and having a cylindrical portion secured loosely to said crank between the two members of the piston.

3. In a rotary-pump, a casing comprising a cylindrical portion having an inlet and an outlet, and an abutment-chamber between the said inlet and outlet, a crank-shaft passing through said cylindrical-portion, a piston comprising two members secured to said shaft on opposite sides of the crank thereof, and an abutment comprising a flat-portion.

movable in said abutment-chamber and a cylindrical portion secured loosely to said crank between the two members of the piston; said cylindrical portion comprising a part integral with said flat-portion, a cap secured to said integral part, and a curved face-plate fitting over said cap and having its ends secured to said integral part.

4. In a rotary pump, a casing having an inlet and an outlet, a crank-shaft passing through the casing, a piston comprising two members secured to said crank-shaft at opposite sides of the crank thereof, and an abutment positioned between said inlet and said outlet and having a flat-portion and a cylindrical-portion secured loosely to said crank between the two members of the piston; the inner edge of the flat-portion of said abutment bearing against the piston-members.

In testimony whereof, I have affixed my signature in the presence of two subscribing witnesses.

RASMUS P. CHRISTENSEN.
